TUNING DEVICE

Bertram A. Schwarz and James G. Funk, Kokomo,
Ind., assignors to General Motors Corporation,
Detroit, Mich., a corporation of Delaware

Application January 6, 1940, Serial No. 312,680

7 Claims. (Cl. 192—142)

The present invention relates to a radio tuning mechanism and more particularly concerns manually and automatically controlled power-operated indexing means for controlling the tuning mechanism.

In prior mechanisms of the above type a reversible electric motor was usually provided for actuating the indexing means. In some mechanisms the motor was directly connected to the indexing means and control means was provided to reverse and stop rotation of the motor in a given angular position by mechanical and electric control means, both of which were manually and automatically actuated. In other mechanisms the motor was connected to the indexing means by a clutch which was disengaged and the motor deenergized after the tuning mechanism had been rotated by the motor in either direction to a given angular position. The controls for either of these two types of mechanisms were complicated and required mechanical and electrical interlocks which were expensive and subject to failure.

In the present invention the tuning mechanism is actuated by spring-operated indexing means, and non-reversible power-actuated means is provided to tension the spring means and limit the rate of movement of the spring-operated indexing means. The control means for both the spring-operated and power-actuated means is simplified as no reversing control is required and no control means is necessary to stop operation of the power-operated means in a definite angular position. This constitutes the principal object of our invention.

The means by which this and other associated objects are accomplished is described in the following specification and illustrated in the accompanying drawings, in which:

Figure 1 is a top plan view of the tuning mechanism in which automatic indexing means is included;

Figure 2 is a side elevation of the mechanism with some of the parts broken away and others shown in section to show details thereof;

Figure 3 is a diagrammatic view showing manually and automatically actuated electrical control devices and the circuit connections extending therebetween to control the spring-operated indexing means and power-actuated means;

Figure 4 is a side elevation of the mechanism with some of the parts broken away and others shown in section to show details of a power-actuated means of slightly different form.

Referring to the drawings, 1 represents a housing which encloses the tuning mechanism and means for controlling the mechanism. The housing 1 may also enclose a radio receiver, not shown, having a tuning device, by which the receiver may be tuned by means of a shaft 3 capable of being rotated to different angular positions.

Conventional manual tuning means may be provided for rotating a control shaft 3 to tune the receiver such as a shaft 5 having a worm 7 fixed thereon, the shaft 5 being mounted in any convenient manner so that it may be moved to bring the worm 7 into mesh with the worm wheel 9 fixed to shaft 3, as shown, in order to rotate it or prevent rotation thereof. Movement of the shaft 5 so that the worm 7 is moved out of mesh with the worm wheel 9 permits independent rotation of the worm wheel 9 and shaft 3.

Spring-operated indexing means and power-operated means for controlling the rate of movement and the tensioning thereof are also provided to rotate a gear 13 in either direction to any one of a plurality of preselected angular positions by merely depressing a push button. The gear 13 meshes with a gear 15 also fixed to the control shaft 3 to tune the receiver automatically. The spring-operated and power-actuated means are supported in a hollow cast frame indicated generally at 11. The gear 13 actuated by these means is fixed on the end of a shaft 17 rotatably supported in aligned openings 19 in the vertical end flanges 21 of the frame 11. A plurality of pinions 23 are axially spaced on the shaft 17 by sleeves 25 located therebetween. Each pinion is mounted for angular adjustment on the shaft 17 and any well-known means for connecting the pinions for rotation with the shaft may be used, such as that shown in our Patent No. 2,258,814. The particular means by which the pinions may be connected to the shaft 17 for rotation therewith after having been angularly adjusted with respect thereto forms no part of the present invention.

Vertically spaced rack bars indicated at 27 mesh with each pinion on either side thereof and are slidably mounted in vertically aligned grooves 29 in the upper and lower horizontal flanges 31 and 33 of the frame 1, which are located, respectively, above and below the pinions. The rack bars above and below each pinion meshing therewith are moved transversely in opposite directions when the pinions 23 are connected to the shaft 17 and this shaft is rotated by control shaft 3 which is operatively connected

thereto and is actuated by the manual tuning means described. Either rack bar 27 of a pair meshing with an individual pinion is contacted and moved by a plate 35, which is also slidably mounted in the vertically spaced grooves 29, and is urged into contact with the ends of either of the racks by helical tension springs 37 attached to the plates at 39 and to the frame 11 by brackets 41 fixed to the upper and lower frame flanges 31 and 33. As best shown in Figure 2, when the plate 35 is moved inwardly in the grooves 29 by the springs 37 it will contact and move the upper rack bar 27 inwardly and rotate the pinion 23 and shaft 17 counter-clockwise, and, conversely, inward movement of the lower rack bar by the plate 35 causes clockwise rotation of the pinion 23 and shaft 17. When the ends of both rack bars are moved into vertical alignment the plate 35 will contact both bars simultaneously and further inward movement of the plate will cease and movement of the racks and pinion will also cease. The pinion will accordingly be rotated in either direction to a definite angular position as will the shafts 17 and 3 when any plate 35 is moved inward by the spring 37 to its fullest extent.

Power-actuated means is provided for simultaneously moving all the plates 35 outwardly away from the racks to tension the springs 37 and to also limit the rate of inward movement of any of these plates by the spring 37. This means comprises an electric motor 43 fixed to the lower frame flange 33 and having a pinion 45 rotated by the motor which meshes with a gear 47 fixed on the lower end of a vertical shaft 49 rotatably mounted in an opening 51 in the frame flange 33. A worm 53 on the upper end of the shaft 49 meshes with a worm wheel 55 fixed on a horizontal shaft 57 rotatably supported in aligned openings 59 in the frame end flanges 21. As shown in Figures 1 and 2, a crank arm 60 is fixed on one end of the shaft 57 and a crank disc 61 is fixed on the other end. A cam slot 63 and a cam projection 65 angularly spaced from the slot are provided on the periphery of the crank disc 61. A pair of connecting rods 67 are pivotally connected respectively to the crank arm and crank disc and the opposite ends of these rods are also pivotally attached to a bar 68 supported for reciprocating movement in horizontal slots 69 in the frame end flanges 21. A manually operable switch indicated at 91 and a switch indicated at 103, to be described later, serve to start and stop rotation of the motor 43 which causes the shaft 57 to be rotated clockwise as viewed in Figures 2 and 3. The shaft 57 is normally stopped so that the rod 68, connecting rods 67, and crank disc 61 occupy the positions shown in the above figures, but the shaft 57 may be stopped when the rod 68 has been moved inward by the connecting rods 67 toward the shaft 57 to its maximum inward position. When the shaft 57 is stopped in this position the connecting rods 67 are in a horizontal dead center position and the cam projection 65 on the crank disc 61 is in the top dead center position. Movement of the rod 68 outward or away from the shaft 57 by the motor 43 moves all the plates 35 outward to tension the springs 37 as the rod 68 extends through horizontal slots 36 in the inner face of each of these plates and exerts outward force on the bottom of the slots. Movement of the rod 68 inward toward the shaft 57 by the motor limits the rate of movement of any of the plates 35 which are held in contact with the rod 68 by the springs 37.

The force exerted by the springs on the plate acting through the connecting rods cannot cause rotation of the shaft 57 on account of the irreversible characteristics of the gear train connecting the shaft 57 to the motor.

A modified structure for moving the plates outward and controlling the rate of inward movement thereof is shown in Figure 4. This structure consists of a plurality of cams 70 fixed on the shaft 57 for operating plates 35a which also have springs 37 attached thereto tending to urge the inner edge of the plates into contact with individual cams 70 which control the reciprocating movement of the plates 35a which operate rack bars 27 in the same manner as described previously. The cams may be of different contour from that shown so that any desired rate of movement of the plates 35a in either direction may be obtained when the cams 70 are rotated by the motor 43. The toe of the cams 70 shown in Figure 4 is on the horizontal center line of the shaft 57 but is rotated clockwise through a small angle from this position when the motor is stopped with the cam slot 63 in the top dead center position as shown in Figure 3, and when the cam projection 65 is in the top dead center position the toe of the cam 70 is rotated 180 degrees clockwise from the position shown in Figure 4.

A plurality of manually releasable latches indicated at 71 are provided to retain each of the individual plates 35 or 35a in substantially their maximum outward position when moved to this position by either the rod 68 or the cams 70 respectively. The rod 68 and the cams 70 may be moved out of contact with the plates 35 or 35a when they are in the latched position, if desired, by causing the motor 43 to be stopped so that the shaft 57 is rotated through a slight angle beyond the position where the plates were engaged by the latches. The latches 71 are pivoted on a bar 72 extending transversely to the path of movement of the plates. The ends of the bar 72 are fixed in any convenient manner to the housing 1. Each latch 71 has an inwardly projecting arm 73 having a beveled end 74 and a notch 75 adjacent thereto which engages a lug 76 integral with each plate when the plate is moved to approximately its maximum outward position. Downwardly projecting arms 77 on each of the latches 71 are normally held in contact with the inner ends of individual push buttons 79 slidably mounted in an opening 81 in the vertical flange 83 of the housing 1 by a rod 85 having an insulated sleeve 87 mounted on the rod intermediate the ends thereof and bearing on the inner sides of all the arms 77. The rod 85 has cranked end portions 89 bent around the bar 72 and is moved angularly with respect thereto by any latch 71 when its respective push button is depressed to release the plate held by this latch.

An electric control switch indicated at 91 is associated with the rod 85 to control energization of the motor to cause it to rotate when any latch 71 is released. This switch has three parallel spring contact blades 93, 95 and 97, the lower ends of which are embedded in an insulated base member 99 fixed to the vertical flange 83 of the housing 1. The central blade 95 of this switch is longer than the other blades and extends upward inside of the bar 85 and is stressed so that its upper end normally bears on the insulated sleeve 87 to urge it outward into contact with all the arms 77 of the latches to project all the push buttons 79 and hold all the notches 75 in the arms 73 of the latches in en-

gagement with the lugs 76 of the plates 35 or 35a as shown in Figures 1, 2 and 4. The blade 95 also bears on the blade 97 when in this normal position and is out of contact with the blade 93 on the opposite side thereof. An insulated stop member is suitably supported on the housing 1 in spaced relation to the blade 95 to limit inward movement of it and also the push buttons 79.

The switch 103 previously referred to is electrically connected to the switch 91 and both of these switches serve to maintain current flow to the motor 43 or to interrupt the current flow thereto. The switch 103 is best shown in Figure 3 and comprises five parallel spring contact blades 105, 107, 109, 111 and 113, embedded in an insulated base member 104 which is fixed in any suitable manner to the frame end flange 21 adjacent the crank disc 61, as best shown in Figure 1. The blade 111 is longer than the other blades and has a downwardly bent end 112 which normally bears on and follows the periphery of the cam disc 61. The blade 111 occupies the position shown in Figure 3 when the motor is de-energized after tensioning the springs 37 and moving the plates to their latched position. The end 112 of this blade is shown in contact with the bottom of the cam slot 63 and the central portion thereof bears on the end of the blade 113, which exerts upward pressure on the blade 111. When the crank disc is rotated clockwise from the position shown, the end 112 of the blade 111 is moved upward onto the periphery of the disc 61 by the beveled portion of the slot 63 and the blade 111 is moved out of contact with the blade 113 slightly after it is moved into contact with the end 108 of the blade 107 bending this blade upwardly a slight amount. The blade 109 located below the blade 107 has its end normally in contact with the blade 107 and normally exerts a slight upward force thereon so that when the blade 107 is moved upward slightly by the blade 111 the blade 109 remains in contact with the blade 107. When the cam projection 65 having a beveled edge 66 contacts the end 112 of the blade 111 the blade 111 is moved upward a greater amount, which, accordingly, moves the blade 107 upwardly a corresponding amount and causes it to move into contact with the blade 105 above it slightly before it breaks contact with the blade 109 below it. When the cam projection is directly under the end 112 of the blade 111 the shaft 57 has been rotated to a position so that any plate 35 or 35a which has been released by its respective latch 71 is limited by either the crank arm 60 and crank disc 61 or its respective cam 70 to its maximum inward position. When the cam projection 65 is rotated out from under the end 112 of the blade 111 the blade 111 will move down to its original position, causing the blade 107 to move down with the blade 109 slightly before it breaks contact with the blade 105. The end 112 will follow the arcuate periphery of the disc until the disc has been rotated a full revolution by the motor, where it will again enter the cam slot 63 and move the blades of the switch 103 to their normal position as shown in Figure 3. The blade 111 may be grounded, as indicated at 121, to the cast frame 11, the blade 113 is connected to the blade 93 of the switch 91 by a conductor 115, the blade 105 is connected by a conductor 117 to the blade 97 of the switch 91 and the blade 109 is connected to the central blade 95 of the switch 91 by a conductor 119. Both the switches 91 and 103 control energization and deenergization of

the motor winding indicated at M from a battery 123 connected thereto by a conductor 125. The opposite side of the battery is connected to the conductor 119 by a lead 127 and the other side of the motor winding is also grounded to the frame 11 and indicated at 129.

Setting operation

In order to set any spring-operated indexing means so that the control shaft 3 will be moved to a preselected angular position when the push button controlling this means is depressed, the following procedure is followed:

The pinions are released from the shaft and the receiver is tuned to the particular broadcast station desired by rotating the shaft 5, which rotates the control shaft 3 and adjusts the tuning device of the receiver. Rotation of the shaft 3 also causes the shaft 17 to be rotated to a corresponding angular position. The shaft 3 is then held in this position and any one of the push buttons 79 is depressed and held depressed, which moves its respective latch 71 to release the push plate 35 and allows it to contact the rod 68 and at the same time moves the blade 95 of the switch 91 into contact with the blade 93. When these blades are in contact the motor winding M is energized from the battery 123 through the conductors 127 and 129, through the blades 93 and 95 of switch 91, conductor 115 and to ground at 121 through blades 113 and 111 of the switch 103. One side of the motor winding M is also grounded to the frame 11 at 129 and the other side is connected to the battery 123 by the conductor 125 and a circuit is thus completed through the frame 11 which causes the motor to rotate the shaft 57 and crank disc 61 clockwise, which controls the rate of inward movement of the plate 35. Initial rotation of the crank disc moves the blade 111 upward into contact with the blade 107 to establish a holding circuit and then moves out of contact with the blade 113. The holding circuit comprises the conductors 127 and 119, blades 109, 107, 111 of the switch to ground at 121. The motor continues to revolve the disc until the cam projection 65 moves the blade 111 upward, causing the blade 107 to move into contact with the blade 105 and then move out of contact with the blade 109, thus breaking the holding circuit through the blades 109 and 111 to ground at 121 and stopping the motor and the cam disc in this position. It will be evident that as long as the push button is held depressed the blades 95 and 93 of the switch 91 will remain in contact and the blades 111, 107, 105 of the switch 103 will likewise be held in contact as long as the cam projection is under the end 112 of the blade 111. Thus the circuit through the grounded portion of the holding circuit is broken as the switch 111, which is grounded at 121, is now only in contact with the blades 107 and 105, the latter of which can only be connected to the battery by the conductor 117 and switch blades 97 and 95 of the switch 91, and these blades are separated when the push button is held depressed. The motor will remain stopped as long as this button is held depressed, and as the shaft 57 has now been revolved sufficiently to allow the plate to contact and move the racks 27 so that their ends are in vertical alignment, thus stopping movement of the plate in its innermost position, the pinion 23 will have been moved angularly with respect to the shaft 17 to an angular position corresponding to the angular position to which the shaft 17 was rotated by the shafts 3 and 5 when the set was

manually tuned to the desired broadcast station. With the pinion, racks and plate held in this position it is only necessary to connect the pinion to the shaft 17 for rotation therewith and release the push button which allows the blade 95 of the switch 91 to move into contact with the blade 97. The motor will then be energized through the conductor 127, 119, blades 95 and 97 of the switch 91, conductor 117 and to ground at 21 through the blades 105, 107 and 111. The motor will start and rotate the crank disc 61 clockwise to cause initial outward movement of the plates and when the cam projection 65 moves out from under the end 112 of the blade 111 the motor will again be energized through the above holding circuit connections and continue to rotate and move the plate outward to its latched position and finally stop when the end 112 of the blade 111 enters the cam depression 63, opening the holding circuit. All the other indexing means are set in like manner.

With all the indexing means set as described above, the shaft 3 will be rotated to a preselected angular position; in order to tune the radio receiver to a particular broadcast station any one push button is depressed for a short time and then released. Depression of the push button releases a spring-actuated plate and energizes the motor to start rotation of the crank disc which operates the switch 103 to establish the holding circuit and the push button can then be released. The motor will operate until the crank disc has been revolved a full revolution as a circuit is established through the blades 95 and 97 of the switch 71 when the push button is released to energize the motor during the time the blades of the switch 103 are positioned by the cam projection to break the holding circuit through this switch. A full revolution of the shaft 57 controls both the rate of movement of the plate to index the shaft 3 and movement of the plate back to its latched position to tension the springs for subsequent identical operation when released by its respective push button.

The position at which the shaft 57 is stopped after the plate or plates have been moved or their latched position is not critical and may be varied to tension the springs to greater or less extent and the latching means may be operated remotely instead of directly as shown. The structure shown in Figure 4 in which cams 70 are used to control movement of the plates 35a operates in the same manner as described, as the cams and plates are the only difference between the two forms of structure shown. Either form of structure shown and described provides a spring-operated non-reversible power-operated means requiring a simple control apparatus and little manual effort and attention in order to obtain any one of a plurality of broadcast stations by merely depressing a particular push button. The cam structure offers a convenient means for varying the rate of inward or outward movement of the plates.

We claim:

1. In a tuning mechanism for a radio receiver comprising a tuning device capable of angular adjustment, indexing means for adjusting said tuning device to a predetermined angular position, actuating means for said indexing means, resilient means operatively connected to the actuating means, power-actuated means operatively connected to said actuating means to tension said resilient means and to control the rate of movement of said actuating means by said resilient

means, and combined manual and automatic controls for starting operation of said power-actuated means to initially control the rate of movement of said actuating means by said resilient means and to finally stop operation of said power-actuated means after said actuating means has been moved by said power-actuated means to tension said resilient means.

2. In a tuning mechanism for a radio receiver comprising a tuning device capable of angular adjustment, indexing means for adjusting said tuning device to a predetermined angular position, actuating means for said indexing means, resilient means operatively connected to said actuating means, power-actuated means operatively connected to said actuating means to tension said resilient means and to control the rate of movement of said actuating means by said resilient means, manually releasable means for engaging and preventing movement of said actuating means by said resilient means and control means operated by both said last named means and said power-actuated means to initially permit movement of said actuating means by said resilient means at a rate controlled by said power-actuated means, and finally stop operation of said power-actuated means after said actuating means is again reengaged by said manually releasable means.

3. In a tuning mechanism for a radio receiver comprising a tuning device capable of angular adjustment, a plurality of indexing means for adjusting the tuning device to any one of a plurality of predetermined angular positions, actuating means for each of the indexing means, resilient means operatively connected to each actuating means, power-actuated means operatively connected to each actuating means for moving all of said actuating means to tension all of said resilient means, a plurality of manually releasable latches, each of which is arranged to engage and hold a respective actuating means against the force of its respective resilient means, and control means for said power-actuated means comprising a control element movable by any one of said latches upon release of same to initiate operation of said power-actuated means and a second control element movable by said power-actuated means to stop operation thereof after any one of said actuating means has been reengaged by its respective latch.

4. In a tuning mechanism for a radio receiver comprising a tuning device, a plurality of indexing means for adjusting the tuning device to any one of a plurality of predetermined angular positions, actuating means for each indexing means, resilient means operatively connected to each actuating means, power-actuated means for moving all of said actuating means to stress all of said resilient means and to control the rate of movement of any one or all of said actuating means by said stressed resilient means, a plurality of manually releasable latches, each of which is arranged to engage and hold a respective actuating means against the force of its respective stressed resilient means, and control means comprising an element movable by any latch upon the release thereof to start operation of said power-actuated means, and a second control element movable by said power-actuated means to stop operation thereof after any one of said actuating means has been reengaged by its respective latch.

5. In a tuning mechanism for a radio receiver comprising a tuning device capable of adjust-

ment, a plurality of indexing means for adjusting the tuning device to any one of a plurality of predetermined positions, actuating means for each indexing means, resilient means operatively connected to each actuating means, means for moving all of said actuating means to stress said resilient means and for controlling the rate of movement of any one of said actuating means by said resilient means whereby the indexing means actuated thereby will be moved to a predetermined position, an electric motor for driving said last named means, a plurality of manually releasable latches, each of which is arranged to engage and hold a respective actuating means against the force of its stressed resilient means, a source of current, means for connecting said motor to said source of current and for disconnecting said motor from said source, said last named means including a control switch operatively connected to and movable by any one of said latches, a cam-operated switch operatively connected to and driven by said motor, and a plurality of conductors interconnecting said switches whereby said motor is energized upon the release of any latch and deenergized by said cam switch, either upon completion of the movement of any indexing means to a predetermined position by its respective actuating means and resilient means, or after any actuating means has been moved to its latched position to stress its respective resilient means.

6. In a tuning mechanism for a radio receiver comprising a tuning device capable of adjustment, a plurality of indexing means for adjusting the tuning device to any one of a plurality of predetermined positions, actuating means for each indexing means, resilient means operatively connected to each actuating means, power-actuated means for simultaneously moving all of said on said actuating means by said resilient means and for limiting the rate of movement of any one of said actuating means by said resilient means to move any one of said indexing means to a predetermined position, said last named means comprising a rotatable shaft and a plurality of

5 cams fixed thereto on each of which an individual actuating means is normally urged into sliding contact therewith by its respective resilient means, a manually releasable latch arranged adjacent each of said actuating means normally engaging and holding each of said actuating means against the action of said resilient means and control means for starting and stopping operation of said power-actuated means, said control 10 means including a control element actuated upon the release of any latch to supply power to said power-actuated means and a second control element actuated by said power-actuated means to cut off the power supplied to said power-actuated 15 means after any actuating means released by its latch is again engaged thereby.

7. In a tuning mechanism for a radio receiver comprising a tuning device capable of adjustment, a plurality of indexing means for adjusting 20 the tuning device to any one of a plurality of predetermined positions, resilient means operatively connected to each actuating means, power-actuated means for simultaneously moving one or all of said actuating means to stress all of 25 said resilient means and for limiting the rate of movement of any one actuating means by said resilient means to a predetermined position, said last named means comprising a rotatable crank-shaft and means reciprocated thereby toward 30 which all of said actuating means are urged, a manually releasable latch arranged adjacent each of said actuating means normally engaging and holding each of said actuating means against the action of said resilient means and control 35 means for starting and stopping operation of said power-actuated means, said control means comprising a control element actuated by and upon the release of any latch to start operation of said power-actuated means and a second 40 control element actuated by the power-actuated means to stop operation thereof after any actuating means released by its latch has been again reengaged thereby.

CERTIFICATE OF CORRECTION.

Patent 2,296,060.

September 15, 1942.

BERTRAM A. SCHWARZ, ET AL.

It is hereby certified that error appears in the printed specification of the above numbered patent requiring correction as follows: Page 4, first column, line 8, for "conductor" read --conductors--; page 5, first column, line 40, claim 6, for "on said actuating means by" read --actuating means to stress--; and that the said Letters Patent should be read with this correction therein that the same may conform to the record of the case in the Patent Office.

Signed and sealed this 5th day of January, A. D. 1943.

(Seal)

Henry Van Arsdale,
Acting Commissioner of Patents.
